UNITED STATES PATENT OFFICE

WILLIAM B. FOSTER, OF UTICA, NEW YORK, ASSIGNOR TO FOSTER BROTHERS MANUFACTURING COMPANY, OF UTICA, NEW YORK

SPRING CONSTRUCTION

Application filed January 2, 1930. Serial No. 417,958.

This invention relates to coiled spring structures or coiled spring assemblies meaning to include thereby such coiled spring structures as are used for spring cushions, 5 spring-filled mattresses, bed springs and the like.

My invention has for its purpose the providing of an improved and novel arrangement and form of such articles and particularly to provide a construction wherein the end coils of the springs are equipped with over-lapping offset portions connected by spiral wire threaded thereonto so as to form a hinged connection between adjacent springs. 15 A further purpose is to provide a construction of the type indicated where the coiled springs may be easily formed and rapidly connected by hand or even by machinery by the use of the said spiral wire and to so form 20 the parts and assemble the same that a flexible but very strong and durable spring structure is secured.

Another object of the invention is to provide a construction of the class indicated of 25 such form and combination of its parts that the overlapping offsets will be securely and permanently held and maintained in said overlapping relation within the spiral wire and will be prevented from reversing their 20 position within the spiral wire and also prevented from piling; and further to provide a joint of the construction referred to wherein the overlapping offset parts of adjoining connected springs will be prevented from overlapping 25 to a greater extent than desired and also will be prevented from straightening out or separating from the original overlapping position, and also to prevent relative movement of the springs and spiral wire length- 40 wise of the spiral wire.

Heretofore one of the disadvantages of joints made with the use of spiral wire has been that the joints allow too much expansion or contraction at the joints and that such loose 45 motion has prevented the satisfactory use of spring structures of this type where the total width of the spring structure should be definite and permanent such as in a bed spring or the filling for a spring mattress. The 50 overcoming of such disadvantages and the

providing of a spring structure which will permanently retain its width free from either expansion or contraction and from piling is the further aim of this invention.

Further purposes and advantages will appear from the specification and claims herein.

Fig. 1 is a plan view of a part of a spring structure embodying this invention.

Fig. 2 is a plan view on a considerably enlarged scale of one of the joints shown in 60 Fig. 1.

Fig. 3 is a cross sectional view on line 3—3 of Fig. 2.

Figs. 4 and 5 are sectional views somewhat diagrammatic taken on lines 4—4 and 5—5 65 respectively of Fig. 2.

Fig. 6 is a plan view of a modified form of joint embodying this invention.

Fig. 7 is a sectional view on line 7—7 of 70 Fig. 6.

Figs. 8 and 9 are sectional views somewhat diagrammatic on lines 8—8 and 9—9 respectively of Fig. 6.

Referring to the drawing in a more particular description it will be seen that a 75 spring structure embodying this invention comprises a plurality of coiled springs 11 having their end coils 12 provided with outwardly extended offset portions 13. The offset portions of adjacent springs to be joined 80 therethrough are oppositely arranged, that is project towards each other and with the offsets of a pair of connected springs in overlapping engagement and connected by a spiral wire 14 threaded upon the overlapping 85 offsets of the two springs.

While my invention as indicated by certain of the claims herein may be applied in a unit having only two adjacent springs with their offsets connected by such spiral wire, 90 yet in the full and ordinary embodiment of the invention there will be a considerable number of coiled springs arranged in two or more rows extending transversely or longitudinally of the cushion or other spring structure and with the springs in adjacent rows oppositely arranged preferably at regular intervals, and with the springs of each adjoining pair of rows connected by a long length of spiral wire. In Fig. 1 a part of 100

such a larger construction is shown but it will be apparent that the same joint and same overlapping feature is present in the two-spring unit such as is illustrated in Figs. 5 and 6.

Referring first more particularly to the construction shown in Figs. 1 to 5 it will be seen that each spring is provided with an offset portion generally denoted by the numeral 13, projecting outwardly from the spring towards another spring which is likewise provided with such an offset portion 13 and that the two offsets engage each other in overlapping position. In the construction shown in detail in Figs. 1 to 5, the offset portion generally denoted by the numeral 13 is composed of a central portion 13^a and two end portions 13^b and 13^c, which end portions extend outwardly from the end coil 12 rather abruptly while the central portion 13^a extends the desired distance in a gentle curve or crowned shape.

Preferably in all forms of this invention the two connected and overlapping offset portions 13 brought into one joint will vary in length. For instance as shown in Fig. 2, three turns of the spiral wire are enclosed on the inner side of the offset 13 of the right hand spring while the offset of the left hand spring is enough longer to contain on its inner side four turns of said spiral wire. This arrangement of one offset portion of a pair being longer than the other offset portion by the distance from one turn to another of spiral wire allows of the springs being connected accurately in intersecting rows at right angles to each other and also aids in securing the full benefit of the overlapping joint and aids in so placing and assembling the parts at the joint so that the joint will be permanently held with the offset parts overlapping and free from expansion or contraction, and also aids in keeping the joint parts in place lengthwise of the spiral wire.

Referring to the construction shown in Figs. 6 to 9 it will be seen that the offset parts are held in overlapping position by the spiral wire and that the offset portion from the left hand spring is longer than the offset portion of the right hand spring. The modification shown in these figures consists in a modification of the form of the offset from the right hand spring. In this construction the offset of said right hand spring consists of one substantially similarly curved portion having a radius preferably less than that of the crowned portion of the offset of the left hand spring and very much less than the radius of the end coil 12 of the right hand spring itself. In other words, the offset of the right hand spring is formed by one section of a circle extended out from the main circle of the end coil 12 without the central portion being flatter than the end portions.

In all forms of the joint used in this in-

vention it will be seen that the interior diameter of the spiral wire 14 is appreciably more than twice the diameter of the wire used in the coil springs and the offsets thereof so as to allow the offset portions of two springs brought into a joint to pass one another to a greater or less extent as seen in the central transverse sectional views Figs. 3 and 7. It will be obvious that the center of the two wires of a pair of offsets must be past each other on this central transverse section and preferably the central portions of the offsets will be slightly but bodily past each other as shown in Figs. 2 and 3 and Figs. 6 and 7.

The offset portions 13 of any of the different forms are so shaped, curved, formed and proportioned relative to the size and turns of the section of spiral wire threaded over said overlapping offsets that the overlapping offset portions will be permanently retained in said overlapping position.

In other words each offset will be so proportioned relative to its section of the spiral wire within which it is placed as to engage at different parts of its length the opposite interior sides of the spiral wire and thus keep the offset from moving to any considerable extent laterally within the spiral wire. For instance the offset portion 13 of the right hand spring in Fig. 2 will engage the interior surface of the spiral wire 14 towards the left at the two points 16-16 where two turns of the spiral wire are engaged by the outer and somewhat upper surface of the central portion 13^a of this offset as shown particularly in Fig. 3. While the more abruptly slanting end portions 13^b and 13^c of the offset will engage towards the right at points 17 and 18 respectively the two spaced turns of the spiral wire as appears in Fig. 2 and in Figs. 4 and 5 respectively. The engagement at points 17 and 18 on the inner side of the relatively rigid offset 13 by contacting the opposite sides of two spaced turns of the spiral wire 14 will prevent relative lateral movement of this offset farther towards the right relative to the spiral wire 14, and will prevent movement of the offset in either direction lengthwise of the spiral wire.

Similarly the relative lateral position of the lower and longer offset of the left hand spring and its position lengthwise of the spiral wire will be maintained by engagement of the outer or right-hand side of the central portion 13^a with the interior surface of the adjacent right-hand side of one turn of the spiral wire as at point 19 as appears in Figs. 2 and 3 and by engagement at the widely-spaced points 20 and 21 respectively where the interior surface of the left-hand part of the spiral wire is engaged with the offset 13, point 20 being near the junction of the central portion 13^a and the end portion 13^b and point 21 being near the junction of the central portion 13^a and the other end portion

13^c. These contacting points appear in Figs. 2, 4 and 5.

It will be understood of course that the two separate offsets will be held in fairly close engagement with their respective parts of the spiral wire by the fact that the two offsets brought together in one joint overlap so that each offset keeps the other in its own half of the circular space within the spiral wire. 5 That is assuming that the offset of the left hand spring is assembled as shown in the drawing below the offset from the right hand spring, said offset from the left hand spring will keep the offset of the right hand spring 10 always in the upper half of the interior space of the spiral wire and in turn the offset from the right hand spring will permanently keep the offset from the left hand spring in the lower half of the interior of the spiral wire. 15 20 It is to be noted, however, that the engagement of the two offsets at a joint with each other and with the encircling spiral wire is not so tight but that the desired amount of pivotal or hinging action between the two 25 springs may take place but the contact is tight enough and constantly maintained so that there is no noise from such pivotal or hinging movement.

It will be apparent that in the modified 30 form of joint shown in Figs. 6 to 9, the offset 13 from the left hand spring is of the same form and detailed description and operation as the same part shown in Figs. 1 to 5 and that the offset from the right hand spring is 35 mechanically the equivalent of and will operate in the same way as the offset from the right hand spring in Figs. 2-5 already described. The one continuous curve used in this offset of Figs. 6-9 will result in two 40 points of contact 16' at the left hand side of the spiral as shown in Fig. 7 and in two spaced points of contact 17' and 18' as shown in Figs. 8 and 9 respectively. These oppositely arranged and spaced points of contact will maintain the relative lateral position between the offset of the said right hand spring and the enclosing portion of the spiral wire and the other offset at that joint, and will also maintain the spiral wire and the offset in proper 50 position against relative movement lengthwise of the spiral wire.

It will be noted that the overlapping offsets at any joint are tied together by the spiral wire as far as vertical movement is concerned 55 so that each spring is directly reenforced at each of these joints by the adjacent spring which operates to distribute local weight or strain over a larger area of the spring structure and increase the life, usefulness and 60 comfort of the spring. This tying together of the springs at these connected offsets however is effected through the encircling spiral wire and in such a way that a pivotal joint is maintained so that the spring structure is 65 still properly flexible so that the structure

is comfortable in use and can be rolled or folded.

It will now be seen that I have produced a spring structure accomplishing the objects and obtaining the advantages hereto outlined 70 and particularly that I have provided a structure where the joints will not expand nor contract nor pile nor allow movement of the springs lengthwise of the spiral wire and yet will be flexible, comfortable, durable and of 75 wide adaptability.

It will be observed that of the turns of the spiral wire within the offset from the right hand spring at any joint, the opposite end turns engage quite closely the adjacent opposite inner sides of the end parts of the offset and so maintain this spring and the spiral wire from relative movement lengthwise of the spiral wire and that similarly of the turns of the spiral wire within the offset of the left hand spring the opposite end turns are quite close to the adjacent opposite inner sides of the end parts of this offset and so maintain this left hand spring and the spiral wire from relative movement lengthwise of the spiral 80 wire. This co-operation of the parts is further aided and made permanent by said spiral wire enclosing both offsets at a joint so that both springs are held in desired position relative to each other, viz: free from movement 85 lengthwise of the spiral wire. The engagement of the opposite sides of the two turns of the spiral wire enclosed within an offset is maintained because the two offsets are kept securely in overlapping position by the special 90 form of the overlapping offsets relative to the spiral wire as already described.

What I claim as new and desire to secure by Letters Patent is:

1. In a spring assembly, a pair of coiled springs each having an outwardly offset portion with said offset portions arranged opposite to each other and in overlapping engagement with each other and a spiral wire extending between said springs and threaded upon the overlapping pair of offset portions and forming a hinged connection between said springs, the interior diameter of said spiral wire being more than twice the diameter of the wire of the coiled springs, each of the said offset portions being intermediate its length extended outwardly relative to the axis of its spring so that its middle part engages the inner surface of the half of the spiral that is farther from the axis of the 105 spring having said offset and with the parts of the said offset near its opposite ends engaging the half of the spiral that is nearer to the axis of said spring whereby both offsets are retained in their originally-assembled overlapping position, one offset of a joint spanning more turns of the spiral wire than the other offset whereby said opposing offsets and their springs are held in central alignment by the spiral wire. 110 115 120 125 130

2. In a spring structure, the combination of a plurality of rows of coiled springs with the springs in adjoining rows oppositely disposed and provided with offset portions in 5 overlapping engagement with each other and a spiral wire extending between each pair of adjoining rows of springs and threaded upon the several pairs of said overlapping offset portions and forming a hinge connection 10 between the springs, the interior diameter of said spiral wire being more than twice the diameter of the wire of the coiled springs, each of the said offset portions being intermediate its length extended outwardly 15 relative to the axis of its spring so that its middle part engages the inner surface of the half of the spiral that is farther from the axis of the spring having said offset, with the parts of the said offset near its opposite 20 ends engaging the half of the spiral that is nearer to the axis of said spring, spaced turns of said spiral wire being located within each offset and close to the end parts of said offset portions, whereby both offsets of each 25 overlapping pair are retained in their originally-assembled position and the successive pairs of springs of each two adjoining rows of springs are held from movement lengthwise of said spiral wire, each offset of a pair 30 of offset portions spanning a plurality of turns of the spiral wire and with one offset of a pair spanning more turns of the spiral wire than the other offset whereby the opposing offsets and their springs are held in 35 central alignment by the spiral wire.

In witness whereof I have affixed my signature, this 21st day of December, 1929.
WILLIAM B. FOSTER.
